(57) **CLAIM**

The ornamental design for a beach tent, as shown and described.

DESCRIPTION

FIG. 1 is a front, left side, top perspective view of a beach tent showing my new design;

FIG. 2 is rear, right side, bottom perspective view thereof;

FIG. 3 is front, left side, bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged partial view of a portion of the beach tent taken from FIG. 1;

FIG. 11 is an enlarged partial view of a portion of the beach tent taken from FIG. 2; and,

FIG. 12 is an enlarged partial view of a portion of the beach tent taken from FIG. 8.

The dash-dot broken lines represent the boundaries of the enlarged partial views of FIGS. 10-12 and form no part of the claimed design.
